CONVERSION OF HIGHER BOILING HYDRO-CARBONS TO LOWER BOILING HYDRO-CARBONS

Victor Henny, London, England, assignor, by mesne assignments, to Universal Oil Products Company, Chicago, Ill., a corporation of Delaware

Application May 7, 1930, Serial No. 450,327
Renewed July 25, 1935

4 Claims. (Cl. 196—48)

This invention relates to the conversion of higher boiling hydrocarbons to lower boiling hydrocarbons, and pertains in its specific embodiment to the separation of a tar oil suitable as cracking stock from the vapors and gases derived from the carbonization of bituminous materials and the conversion of same at elevated temperatures into anti-knock motor fuel and other products.

10 It is among the objects of my invention to make use of low grade coals and coal wastes as well as the higher grade coals in the production of coke and high anti-knock motor fuel. The carbonaceous materials used include bituminous 15 coals, cannel coal, brown coal, lignites, peats, etc. My invention is directed particularly toward the treatment of the condensable vapors produced in the carbonization of these materials.

Among further objects of my invention is to 20 provide a process where the carbonization process and cracking operation are combined, i. e., a process where the vapor and gaseous products from the carbonaceous process are treated and a tar oil suitable as cracking stock separated and 25 subjected to conversion conditions. Advantages are obtained such as heat economy, reduction or elimination of high coke-forming constituents in the cracking stock, improved yields and quality of the products, etc.

30 The carbonization stage of the process is preferably of the low temperature type in which the carbonaceous material is subjected to the relatively low temperature treatment of approximately 750—1000° F., or more, where higher yields 35 of oil for cracking are obtained than in high temperature carbonization and decreased yield of coke and gaseous products. The coke is a desirable, smokeless fuel, and the gases have a much higher heating value than the gases obtained in high temperature carbonization.

40 My invention comprises the treatment of the vapor and gaseous products from the carbonization process, separating the uncondensable gases and light condensable fractions which include 45 motor fuel hydrocarbons and condenses a tar oil suitable for cracking stock. The light condensable vapors are separated from the uncondensable gases by condensation, and the uncondensable gases may be subsequently processed for recovery 50 of condensable products. The tar oil condensate is directed to the conversion stage of my process without substantial cooling below its condensation temperature.

55 The invention will be more clearly understood by referring to the attached drawing which will

be described later, and in which the preferred embodiment of the conversion stage of the process is illustrated. The temperature conditions used at the outlet of the heating element from which the mixture of heated cracking stock and partially converted materials therefrom are passed to a reaction zone, may vary from 800° to 1100° F., more or less, and the pressure may vary from high superatmospheric pressure to atmospheric or sub-atmospheric pressure. The pressures on 10 the system may be uniform, varying only by the friction or natural pressure drop through the various elements, or differential pressures may be used by the manipulation of the various valves, or other means indicated.

15 Referring now to the attached drawing, which is a diagrammatic side elevation not drawn to scale, the tar oil vapors from the retorts of a continuous carbonization process (not shown) are introduced through line 1 and valve 2 to the 20 condensing column 3 containing suitable dephlegmating means which cause condensation and separation of the tar oil fraction which is to be cracked. A suitable cooling medium is used in the condensing column 3 and is introduced from 25 a source (not shown) through line 4 and valve 5 to the suction side of pump 6 which pumps this oil through line 7 and line 8 with valve 9 by suitable regulation of this latter valve and valve 10 in line 11. Cooling may also be effected at the 30 top of condensing column 3 by the introduction of another cooling medium introduced through line 12, regulated by valve 13, from a source which will be later described. Uncondensed vapors and non-condensable gases leave the top 35 of the condensing column 3 through line 14 and valve 15 leading to the condenser and/or cooler 16, and are then directed through line 17 and valve 18 to the receiver 19 where separation of the liquid and gases is effected. The non-condensable gases are removed through line 20, regulated by valve 21, and may be directed to the low pressure gas line 22 and distributed as will be later described, or may be removed through line 23, regulated by valve 24, and disposed of in any 40 suitable manner. The liquid in receiver 19 is removed through line 25, regulated by valve 26. The tar oils condensed in the condensate column 3 flow downward through line 27 and valve 28 to the suction side of the hot feed pump 29 from 50 which the oil is pumped through line 30 and valve 31 leading to the dephlegmator 32 and/or through the regulating valve 33 in line 34 into the line 35 where valve 36 may be closed, and then through valve 37 into line 42 where it mixes with reflux 55

condensate oil and passes to the heating element which is about to be described. The oil introduced to dephlegmator 32 through line 30 and/or line 38 (as will be later described) may come in direct, and possibly indirect, heat transfer relationship with the vapors therein and the condensed oil, reflux condensate, so-called, together with the added hydrocarbon oil directed downward through line 39 and valve 40 to the suction side of a hot oil pump 41 which pumps this oil through line 42 and valve 43 to the heating coil 44 located in heating zone 45. The heated products leave the heating coil 44 through line 46 and valve 47, and pass to the reaction zone 48 where the reaction continues and vaporization, separation and/or deposition take place. Non-vaporized oil may be withdrawn through line 49, regulated by valve 50, and may be directed to storage or any other suitable disposal. The vapors and gases leave the reaction zone 48 through line 51 and valve 52 and enter the dephlegmator 32 where they are subjected to heat interchange, dephlegmation and cooling, which has been or will be further described. The treated vapors leave the dephlegmator 32 and pass through line 53 and valve 54 leading to the condenser and/or cooler 55, and the cooled products flow through line 56 and valve 57 into the receiver 58 where separation of the liquid product and non-condensable gas is effected.

The uncondensable gases are removed through line 59 and may be directed through valve 60 to the low pressure receiver 61 or through valve 62 in line 63 leading into line 22, from which it may be directed to storage through line 64, regulated by valve 67, or may be directed through line 68, regulated by valve 69, to the heating zone 45 or to other suitable disposal. The liquid product from the receiver 58 is withdrawn through line 70, regulated by valve 71, and is directed to the low pressure receiver 61 where the dissolved gases are separated and released at reduced pressure. The released gases are withdrawn through line 72 and may be introduced into line 22 by regulation of the valve 73, or may be released by valve 74 from which they are directed to recovery plant. The regulated portion of the liquid products in receiver 58 may leave through line 75, regulated by valve 76, and flow to the suction side of pump 50 77 which may pump this oil through line 78 and valve 79 to the dephlegmator 32 and/or through the line 12 and valve 13, as previously described. The liquid product from the receiver 61 is withdrawn through line 65, regulated by valve 66.

55 Any desired portion of the oil introduced through line 4 and pumped by pump 6, previously referred to, may be directed through valve 10 in line 11 into line 38 leading to dephlegmator 32 by the suitable regulation of valves 80, 81, and 60 82, and/or a portion or all of this oil may be directed through valve 82 in line 11 into the line 35 leading to the hot oil being pumped to the heating element 44. During operation of the plant, valves 37 and 36 are usually open so that in case 65 of emergency valve 83 can be readily opened and the contents of the heating coil 44 dumped.

70 As an illustration of the application of the process of my invention and results obtained in connection with a continuous, low temperature carbonization process where cannel coal is being processed, the vapors and gases produced are directed to the condensing column 3, diagrammatically illustrated in the drawing above described. Approximately 6% to 7% of the total 75 condensable materials pass over to the condenser

together with the uncondensable gases and are separated as motor fuel. A 24 gravity topped crude oil is pumped into the condensing column 3 through line 8 which serves to condense the tar oil vapors and furnish additional cracking stock 5 for the process. The mixture of petroleum oil and coal tar condensate, which is approximately 50% of each, is withdrawn from the condensing column and pumped to the dephlegmator 32 of the conversion process. Although many types of 10 operation are possible in the conversion process, such as various forms of residuum operation producing varied amounts of coke as a by-product, the operation here illustrated is of the non-residuum type in which substantially no non-vaporized residue oil is withdrawn from the reaction chamber 48, a hard, agglutinated coke being deposited therein and all liquid products being removed from the vapors and gases leaving the top of the reaction chamber and passing to the 20 dephlegmator. The temperature of the oil leaving the heating element is approximately 930° F. and the pressure approximately 350 pounds per square inch. A temperature of approximately 500° F. is maintained at the top of the dephlegmator 32 by recirculating the condensed and cooled overhead product from same. The pressure on the system is controlled in the present operation at two points, first in line 46 where the pressure is reduced from approximately 350 30 pounds to 200 pounds per square inch by the regulation of valve 47, and, second, by maintaining a liquid level in the receiver 58 and releasing the gas from the top of the receiver by means of valve 60.

The refined motor fuel resulting from this operation represents approximately 62% based on the total oil charged to the conversion stage of the process. The motor fuel has an end point of approximately 420° F., and has an anti-knock 40 value of approximately 40% benzol in Pennsylvania straight-run gasoline.

My invention should not be construed as being limited to the above examples of operations or the yields and character of products described, these being given for illustrative purposes only.

I claim as my invention:

1. A process for producing low boiling point oils from heavy petroleum oil and from the vaporous mixture produced in the carbonization of solid pyrobituminous materials which comprises dephlegmating said vaporous mixture in a fractionating zone to condense and separate heavier fractions therefrom, condensing the lighter vapors uncondensed by the dephlegmation, passing the condensed heavier fractions in admixture with said petroleum oil in a restricted stream through a heating zone and subjecting the mixture therein to cracking conditions of temperature and pressure, discharging the heated mixture into a vapor separating zone and separating the same therein into vapors and residuum, subjecting said vapors to reflux condensation in a second fractionating zone independently of said vaporous mixture to condense fractions thereof heavier than the desired low boiling point oils, returning resultant reflux condensate to the heating zone for further cracking treatment therein, finally condensing the vapors uncondensed by said reflux condensation thereby forming pressure distillate, and introducing a portion of said pressure distillate into direct contact with said vaporous mixture undergoing dephlegmation in the first mentioned fractionating zone.

2. A process for producing low boiling point oils from the vaporous mixture produced in the carbonization of solid pyrobituminous materials and simultaneously from petroleum charging stock for a cracking operation, said process comprising subjecting the petroleum charging stock to cracking conditions of temperature and pressure in a cracking zone, removing the cracked vapors and dephlegmating the same in a fractionating zone, 5 simultaneously dephlegmating said vaporous mixture in a fractionating zone independently of said vaporous mixture in contact with fresh petroleum charging stock, introducing the resultant mixture of reflux condensate and charging stock to the first-mentioned fractionating zone as a direct 10 contact dephlegmating medium in the dephlegmation of said cracked vapors, and then supplying said resultant mixture together with reflux condensate formed by the last-named dephlegmation to the cracking zone.

3. A process for producing low boiling point oils from the vaporous mixture produced in the carbonization of solid pyrobituminous materials and simultaneously from petroleum charging stock for a cracking operation, said process comprising dephlegmating said vaporous mixture in a fractionating zone in contact with the petroleum charging stock, thereby forming a mixture 15 of tar oil condensate and petroleum charging stock, supplying the last named mixture to a cracking zone and cracking the same therein, 20 fractionating the cracked vapors thus formed in a second fractionating zone independently of said vaporous mixture to condense heavier fractions thereof and returning resultant reflux condensate to the cracking zone, finally condensing the fractionated cracked vapors and introducing a portion 25 of the resultant final condensate into contact with said vaporous mixture undergoing dephlegmation.

cracking zone and cracking the same therein, dephlegmating the cracked vapors in a second fractionating zone independently of said vaporous mixture to condense heavier fractions thereof, combining reflux condensate formed in the second fractionating zone with the mixture of tar oil condensate and petroleum charging stock being supplied to the cracking zone, and finally condensing the dephlegmated vapors.

4. A process for producing low boiling point oils from the vaporous mixture produced in the carbonization of solid pyrobituminous materials and simultaneously from petroleum charging stock for a cracking operation, said process comprising dephlegmating said vaporous mixture in a fractionating zone in contact with the petroleum charging stock, thereby forming a mixture of tar oil condensate and petroleum charging stock, supplying the last named mixture to a cracking zone and cracking the same therein, 20 fractionating the cracked vapors thus formed in a second fractionating zone independently of said vaporous mixture to condense heavier fractions thereof and returning resultant reflux condensate to the cracking zone, finally condensing the fractionated cracked vapors and introducing a portion 25 of the resultant final condensate into contact with said vaporous mixture undergoing dephlegmation.

VICTOR HENNY. 30
